UNITED STATES PATENT OFFICE.

WILLIAM A. BREWER, OF PITTSBURGH, AND EDWARD F. HOPPEL, OF NEW KENSINGTON, PENNSYLVANIA, ASSIGNORS TO P. H. MURPHY COMPANY, OF PARNASSUS, PENNSYLVANIA, A CORPORATION OF PENNSYLVANIA.

CAR-ROOF.

1,302,298.

Specification of Letters Patent. Patented Apr. 29, 1919.

Application filed December 13, 1918. Serial No. 266,567.

To all whom it may concern:

Be it known that we, WILLIAM A. BREWER, a citizen of the United States, and a resident of the city of Pittsburgh, county of Allegheny, and State of Pennsylvania, and EDWARD F. HOPPEL, a citizen of the United States, and a resident of the city of New Kensington, county of Westmoreland, and State of Pennsylvania, have invented a new and useful Improvement in Car-Roofs, of which the following is a specification.

This invention relates to flexible car roofs of the type shown in C. C. Murphy Patent No. 1,133,493 dated March 30, 1915 wherein the roof sheets are pivoted near their ridge ends to the roof sheathing and are connected along their side and ridge margins by flexible seams; and it relates particularly to the ridge construction of roofs of this type. In roofs of said type, the running board saddles, which support the running boards, and the intermediate anchor saddles, which hold the roof sheets down on their respective pivots, are secured to the roof substructure by means of bolts; and it is important that these saddles be kept tight at all times to secure a water tight roof. In actual practice, these wooden saddles sometimes become loose and permit leakage; and, among the conditions which contribute to this effect, are the following: the rotting and wearing of the saddles around the bolt holes; the shrinking of the saddles, roof sheathing and ridge poles; and the loosening of the nuts on the saddle bolts during the service of the car. In roofs of said type, another practical disadvantage is that the wooden intermediate anchor saddles, which are recessed on their under sides to receive the bosses of the roof sheets, are liable to split in the region of the recesses and thereby permit the sheets to become disengaged from their pivots.

The principal objects of the present invention are: to improve the ridge construction of the car so as to overcome the disadvantages hereinbefore mentioned; to eliminate the intermediate anchor saddles and ridge corner caps; to improve the joints between adjacent ends of the ridge seam covers and the running board saddles; and to keep the ridge seam covers in alinement. The invention consists in an anchor clip for holding the sheets in position at the ridge, and in the improved joint between the adjacent ridge

seam covers and the running board saddles. 55 The invention further consists in the combinations and arrangements of parts herein-after described and claimed.

In the accompanying drawings, wherein like numerals refer to like parts wherever they occur,

Figure 1 is a plan view of a car roof embodying our invention, parts being shown broken away to more clearly illustrate the invention; 65

Fig. 2 is an enlarged transverse section through the ridge portion of the roof, the section being taken adjacent to one of the running board saddles on the line 2—2 in Fig. 1; 70

Fig. 3 is a transverse section through the ridge portion of the roof, the section being taken through the pivot saddle and anchor clip on the line 3—3 in Fig. 1;

Fig. 4 is a longitudinal section of the roof 75 through one of the running board saddles and transverse seams on the line 4—4 in Fig. 2;

Fig. 5 is a longitudinal section of the roof at the ridge through one of the running 80 board saddles at the saddle bolt on the line 5—5 in Fig. 2;

Fig. 6 is a perspective view of one of the sheet anchor clips;

Fig. 7 is a perspective view of one of the 85 ridge cap connector plates;

Fig. 8 is a perspective view of the end portion of one of the ridge seam covers;

Fig. 9 is a perspective view of the ridge end portion of a transverse seam cover; 90

Fig. 10 is a vertical cross-section of the eaves portion of the roof, the section being taken through one of the transverse seam covers on the line 10—10 in Fig. 1; and

Fig. 11 is a vertical cross-section of the 95 eaves portion of the roof, the section being taken between transverse seams on the line 11—11 in Fig. 1.

The roof illustrated in the accompanying drawings comprises roof sheathing boards 100 12 supported at the eaves by metal angle side plates 13, and at the ridge by means of a ridge pole 14, all of any suitable construction. The roof sheets 15 are arranged transversely of the car, side by side, in two rows 105 on opposite sides of the ridge. The roof sheets are arranged in pairs on opposite sides of the ridge, the two sheets of a pair

being disposed end to end in transverse alinement and spaced apart from the adjacent pairs along their side margins to permit mullions 16 to be laid between them. 5 These mullions are arranged in alinement cross-wise of the car, extend transversely of the car from eaves to ridge on opposite sides of the ridge, and are of less width than the space between the side margins of the 10 roof sheets.

The eaves ends of the roof sheets are turned under, as at 17, parallel with the body portion of the sheet but spaced therefrom far enough to accommodate the rebent inner 15 portion 18 of a continuous flashing strip 19. The flashing strip 19 lies in a rabbet formed in the eaves end of the roof sheathing and is turned down over the eaves ends of the sheathing and angle side plate 13. The 20 flashing strip 19 and the eaves ends of the roof sheathing 12 are secured to the side plate by bolts 10 (see Fig. 10) or other suitable securing means, which are preferably located under the eaves ends of the mullions. 25 16. The side and ridge margins of the roof sheets are provided with inwardly hooked upstanding flanges 20 and 21. The side margins of adjacent roof sheets are covered by transverse seam covers 22 which are supported on the mullions 16 arranged between the spaced side margins of the roof sheets. These transverse seam covers are of inverted channel shape in cross-section and their side walls have inturned flanges 23 at the bottom 30 which incline upwardly and interlock with the inwardly hooked upstanding side flanges 20 of adjacent roof sheets. The transverse seam covers extend from ridge to eaves and are held down at the eaves ends by bending 35 40 the eaves ends 24 of their top portions down over the ends of the mullions and then turning said portions under the rebent inner portion 18 of the flashing strip 19. The top portions of the ridge ends of the transverse seam covers have flat extensions 25 which lap at the ridge and are perforated to receive the saddle bolts 26 of the running board saddles 27. Running boards 27^a are secured to the running board saddles 27, 45 which rest on the transverse seam covers 22 and are supported by the mullions 16, thus leaving the sheets free to move under the transverse seam covers.

Each pair of oppositely disposed roof sheets is pivoted to the roof substructure at the middle portion near its ridge end by means of a sheet metal pivot saddle 28. The pivot saddles straddle the ridge portion of the car and are provided near their ends 50 with inverted cup shaped pivot bosses 29 which fit into counterpart upstanding bosses 30 formed in the middle portion of the sheets near their ridge ends. The bosses 30 of each pair of oppositely disposed roof sheets are held in engagement with the pivot, 55

bosses 29 of the pivot saddle 28 by means of a channel shaped anchor clip 31 which has the upper portions of its side flanges bent outwardly and downwardly over the adjacent ridge flanges 21 of the oppositely disposed roof sheets. These anchor clips are located on top of the pivot plate 28, and both of these members are secured in place by means of a bolt 32 which extends down through the roof sheathing and ridge pole. 75

A ridge cover 33 similar in cross-section to the transverse seam covers 22, but of greater width, straddles the spaced ridge margins of each pair of roof sheets, and the lower edges of its side walls rest on the roof sheet and are rebent inwardly, terminating in upwardly inclined flanges 34. The side walls of the ridge seam covers extend from transverse seam cover to transverse seam cover and at each end their top portions have 80 extensions 35 which project over the lapped extension 25 of the transverse seam cover to within a short distance on each side of the saddle securing bolt 26. The extensions 35 at each end of the ridge seam covers have 85 upstanding flanges 36 at their ends which project into vertical saw cuts or grooves 37 cut in the under side of the running board saddles 27.

The adjacent ends of the ridge caps are 90 held in alinement by means of ridge cover connector plates 38 which rest on the lapped extensions 25 of the transverse seam covers and project a short distance into the adjacent ends of the transverse seam cover beneath the top portions of the same. The margin of the portions of the connector plates which project beneath the adjacent end of the ridge seam covers are rebent to form stiffening flanges 39. The connector 100 plates are held in position by means of the saddle bolts 26 which pass through holes surrounded by upstanding bosses 40 located in the center of the connector plates. The bosses 40 of the connector plates are drawn 105 into the under side of the running board saddle when the nut on the lower end of the saddle bolt is drawn up tight. The connector plates, which serve to keep the ridge caps in alinement, will also carry off water 110 that may be blown in under the running board saddles and over the upstanding flanges at the ends of the ridge seam covers, while the upstanding boss 40, which projects into the under side of the running 115 board saddles, prevents this water from following the bolt and reaching the interior of the car. The sheets are held in position on their pivots at the ridge by the anchor clips 31, thereby eliminating the intermediate 120 running board saddles heretofore used for this purpose. The sheets are further held down along the ridge by the wide ridge seam covers, which bear on the roof sheets close 125 to the bosses. The transverse seam covers 130

22 are held in position on the car by the saddle bolts 26 which pass through the lapped extensions 25. These bolts also hold the connector plates 38 in position and secure 5 in position the running board saddles 27, which rest on the transverse seam covers 22 and are supported by the mullions 16. The ridge seam covers 33 are held against movement lengthwise of the car by the upstanding flanges 36 at their ends which fit into the grooves or saw cuts 37 in the under side of the running board saddles 27. By the arrangement described, even though the running board saddles become loose, the water proofing qualities of the joints along the ridge will not be impaired.

The invention is not restricted to the particular shapes and arrangements of parts shown in the drawings.

20 What we claim is:

1. A car roof comprising a pair of roof sheets arranged end to end on opposite sides of the ridge, said roof sheets being spaced apart at the ridge and having upstanding 25 flanges at their ridge margins, and a clip for anchoring each pair of sheets at the ridge, said clip being secured to the ridge of the car between the ridge ends of the sheets and having flanges loosely engaging 30 the upstanding ridge flanges of said roof sheets.

2. A car roof comprising roof sheets arranged in pairs on opposite sides of the ridge, and having inwardly hooked upstanding flanges at the ridge margins, said roof sheets being movably secured to the car at the eaves and pivoted to the substructure near their ridge ends, and clips for anchoring each pair of sheets at the ridge; said 35 clips being secured to the ridge of the car between the ridge ends of each pair of roof sheets and having outwardly hooked upstanding flanges extending over the inwardly hooked flanges of each pair of sheets.

45 3. A car roof comprising roof sheets arranged in pairs on opposite sides of the ridge and having pivot recesses near their ridge ends, said roof sheets being movably secured to the car at the ridge and having inwardly hooked upstanding flanges along their ridge and side margins, ridge seam covers connecting the adjacent ridge margins of each pair of sheets, side seam covers connecting the adjacent side margins 50 of said sheets, a metal pivot strip arranged crosswise of the ridge extending beneath each pair of sheets and having pivots engaging the pivot recesses of each pair of sheets, and a channel shaped clip resting on 55 said pivot strip for holding each pair of sheets in engagement with the pivots of the pivot strip, a bolt extending through said pivot strip and channel shaped clip for securing said members to the ridge of the 60 car, the side flanges of said channel shaped

clip being hooked outwardly at the top to loosely engage the adjacent inwardly hooked flanges of each pair of roof sheets.

4. A car roof comprising roof sheets arranged transversely of the car on opposite 70 sides of the ridge, ridge seam covers movably connecting the ridge margins of said sheets, side seam covers movably connecting the side margins of said sheets, running board saddles resting on said side seam covers and adapted to be secured to the roof substructure, said ridge seam covers having upstanding flanges at their ends projecting into the under side of said running board saddles.

5. A car roof comprising roof sheets arranged transversely of the car in pairs on opposite sides of the ridge, the side and ridge margins of said sheets being spaced apart and provided with upstanding flanges, 80 a clip for anchoring each pair of sheets at the ridge, said clips being secured to the car at the ridge and having portions engaging the ridge flanges of each sheet of a pair, side seam covers movably connecting the side margins of the sheets, running board saddles resting on said side seam covers and adapted to be secured to the roof substructure, and ridge covers loosely connecting the ridge margins of the roof sheets, 85 said ridge seam covers being arranged between the side seam covers and having upstanding flanges at their ends projecting into the under sides of the running board saddles.

90 6. A car roof comprising roof sheets arranged in pairs on opposite sides of the ridge, said roof sheets being pivoted to the roof substructure on opposite sides of the ridge, side seam covers movably connecting the side margins of said sheets, said side seam covers being arranged on opposite sides of the ridge and having their adjacent ridge ends lapped, inverted channel shaped ridge seam covers straddling the ridge ends 105 of the oppositely arranged sheets, said ridge seam covers having upstanding flanges at each end, and running board saddles resting on said side seam covers, said running board saddles having grooves in their under side adapted to receive the upstanding flanges at the ends of adjacent ridge seam covers.

110 7. A car roof comprising roof sheets arranged in pairs on opposite sides of the ridge, said roof sheets being spaced apart at their side and ridge margins and pivoted to the roof substructure on opposite sides of the ridge, side seam covers movably connecting the side margins of said roof sheets, inverted channel shaped ridge covers movably 115 connecting the ridge margins of said sheets, said ridge seam covers being located between the side seam covers with their top end portions projecting over the side seam covers on each side thereof, said top end portions 120

125 130

of said ridge seam covers having upstanding flanges at their ends, and running board saddles located above the side seam covers, said running board saddles being 5 adapted to be secured to the roof substructure and having slots in their under sides adapted to receive the upstanding flanges of adjacent ridge covers.

8. A car roof comprising roof sheets arranged in pairs on opposite sides of the ridge, said roof sheets being spaced apart along their side and ridge margins and being pivoted to the roof substructure on opposite sides of the roof, side seam covers 10 movably connecting the spaced side margins of the roof sheets, ridge seam covers movably connecting the spaced ridge margins of the roof sheets, plates located above the side seam covers at the ridge, said plates projecting 15 into the adjacent ends of said ridge seam covers, running board saddles located above said side seam covers and said plates, and means for securing said running board saddles to the roof substructure, said means extending through said plates and said side seam covers at the ridge for holding said plates and side seam covers in position.

9. A car roof comprising roof sheets arranged in pairs on opposite sides of the ridge, said roof sheets being spaced apart along their side and ridge margins and being pivoted to the roof substructure on opposite sides of the roof, side seam covers movably connecting the spaced side margins of the roof sheets, inverted channel shaped ridge seam covers movably connecting the spaced ridge margins of the roof sheets, plates located above the side seam covers at the ridge, said plates having 30 35 40 45 bossed-up holes in their centers and being arranged with their opposite ends projecting into the adjacent ends of said ridge seam covers, running board saddles located above said side seam covers and said plates, and means for securing said running board saddles to the roof substructure, said means extending through the bossed-up holes in

the plates and the side seam covers at the ridge for holding said plates and side seam covers in position.

10. A car roof comprising roof sheets arranged in pairs on opposite sides of the ridge, said roof sheets being spaced apart along their side and ridge margins and being pivoted to the roof substructure on opposite sides of the roof, mullions arranged in the spaces between the side margins of the sheets, side seam covers straddling said mullions and movably connecting the spaced side margins of the roof sheets, said side seam covers being arranged on opposite sides of the ridge and having their ridge ends lapped, inverted channel shaped ridge seam covers movably connecting the spaced ridge margins of the roof sheets, plates located at 60 65 70 75 the ridge above the side seam covers, said plates projecting into the adjacent ends of said ridge seam covers, running board saddles resting on said side seam covers and said plates, said plates having upstanding bosses at their centers adapted to project into the under side of said running board saddles, and means for securing said running board saddles to the roof substructure, said means extending through the upstanding bosses of the plates and side seam covers at the ridge for holding them in position.

11. A car roof comprising relatively movable roof sheets extending from eaves to ridge on opposite sides of the car, ridge seam covers movably connecting the ridge margins of said roof sheets, plates located at the joints between adjacent ends of said ridge seam covers and extending into the adjacent ends of said ridge seam covers, running board saddles located above said plates, and means for securing said running board saddles to the roof substructure, said means extending through said plates for holding said plates in position.

Signed at Parnassus, Pa., this 9th day of December, 1918.
